UNITED STATES PATENT OFFICE.

JOHN J. BOYNE, OF BUFFALO, NEW YORK.

WATER-CLOSET.

1,171,694.

Specification of Letters Patent.

Patented Feb. 15, 1916.

Application filed December 13, 1915. Serial No. 66,505.

To all whom it may concern:

Be it known that I, JOHN J. BOYNE, a citizen of the United States, residing at Buffalo, in the county of Erie and State of New York, have invented new and useful Improvements in Water-Closets, of which the following is a specification.

This invention relates to a water closet of that type in which the contents of the bowl are removed by siphonic action. In closets of this character as heretofore usually constructed the siphon was liable to become clogged by accidentally dropping into the bowl toilet articles such as tooth and hair brushes and also drinking glasses and other articles which are too large to pass through the siphon, thereby causing the bowl to overflow by repeated use and result in damage and inconvenience.

The object of this invention is to provide such water closets with an overflow which extends upwardly farther than the siphon and which during the normal condition of the closet will be inactive but in the event of the siphon becoming clogged, will become active and conduct the water from the bowl to the outlet of the closet and thus prevent flooding the same without, however, causing the contents of the bowl to be wholly withdrawn from the latter but permit the level of the same to rise higher than normally and thus operated as a signal that the closet is out of order and should be corrected.

In the accompanying drawings: Figure 1 is a vertical longitudinal section of a water closet embodying my improvements. Fig. 2 is a horizontal section in line 2—2, Fig. 1. Similar characters of reference indicate corresponding part in both figures.

Although my invention is applicable to water closets which may be variously constructed so far as the details are concerned, that shown in the drawings comprises a bowl 1 having an internal flushing rim 2 and a water supply pipe 3 connected with the rear part of this rim.

Underneath the bowl is arranged the outlet 4 for the closet which may be connected with the drain or soil pipe in any suitable and well known manner. During the normal operation of the closet the contents of the bowl are removed therefrom through a siphon preferably arranged on the rear part of the closet and having an ascending passage 5 which extends upwardly from the bottom or lower part of the bowl and a de-

scending passage 6 extending downwardly from the upper end of the ascending passage 5 to the outlet 4.

Upon admitting water into the bowl from the supply pipe and flushing rim so as to cause the water in the bowl and ascending passage 5 to rise until it escapes into the descending passage 6 a siphonic action is produced in a well known manner which causes the contents of the bowl to be drawn from the bowl upwardly through the ascending passage 5 and discharged downwardly through the descending passage 6 and out of the outlet to the waste pipe. After each flushing operation the water remaining in the bowl seals the lower end of the ascending passage 5 so as to prevent the escape of any sewer gas from the drain pipe through the siphon into the building, the level of the water at this time not rising above the upper ends of the ascending and descending passages of the siphon.

It sometimes happens that the main siphon becomes clogged by reason of children dropping tooth or hair brushes, drinking glasses or other hard substances in the bowl so that they are drawn into the passages of the siphon and choke the same. When this occurs in closets as heretofore constructed the subsequent addition of water upon opening the flushing valve will eventually fill the bowl completely with water and often flow from the top of the latter to the floor causing damage and inconvenience. To avoid this an overflow is provided which is preferably arranged on the front side or part of the closet and which consists of an ascending passage 7 extending upwardly from the bottom of the bowl and a descending passage 8 extending downwardly from the upper end of the ascending passage 7 to the outlet 4. The upper ends of the ascending and descending passages of the overflow are arranged higher than the upper ends of the ascending and descending passages of the main siphon so that no water will flow over the turn or highest part of the overflow while the water is free to flow over the turn or highest part of the siphon. But if the siphon is obstructed either completely or to such an extent that the water is not carried away from the bowl by the siphon as fast as it is supplied by the flush pipe then the water will rise in the bowl and in the ascending passage of the overflow until it reaches the highest part of the same after which any

additional water discharged into the bowl by the flush pipe will flow downwardly through the descending passage of the overflow and escape through the outlet 4 to the 5 drain or sewer. Inasmuch as the ascending passage of the overflow is filled with water from the bowl this overflow is water sealed and sewer gas is prevented from passing through the same from the drain or waste 10 pipe into the building.

It will thus be noted that so long as the siphon is in an operative condition to carry away the contents of the bowl when the flushing water is supplied thereto, the overflow 15 is inactive, but when the siphon fails to carry away the contents of the bowl then the water rises to an abnormal height in the bowl, whereby the overflow becomes active and carries away the water from the bowl 20 to the outlet, thereby preventing flooding of the room in which the closet is installed. When this abnormal rising of the water in the bowl is observed this serves as a signal that something is wrong with the 25 siphon so that a plumber can be called to correct the defect. The closet is not intended to be used when only the overflow is available since the primary function of the latter is that of a safety device to prevent 30 overflowing of the closet and also as an indicator to call attention to a clogged condition of the siphon.

By arranging the auxiliary siphon on the front side of the bowl the closet can be 35 manufactured at low cost without any unusual difficulty and without detracting from the appearance of the same.

The turn connecting the upper ends of the ascending and descending passages of 40 the overflow is preferably located close to the top of the bowl so that any person using the closet in the ordinary way would be liable to get wet and thus operate as a deterrent to use the closet while the same is 45 out of repair.

The descending passage of the overflow is of larger cross section throughout its length than the companion ascending passage so that this descending passage has 50 a larger capacity than the ascending passage coöperating therewith. By this means a siphonic action of the overflow is rendered impossible because the descending passage 8 will carry away the water faster 55 than the ascending passage 7 can supply the same, thereby preventing filling of the descending passage 8 with water so that the

same can at no time operate to siphon out the contents of the bowl. The solid matter in the bowl is usually at the top of the contents while the liquids are at the bottom. It follows from this that only the liquids, as a rule, escape from the bowl through the overflow when the siphon is obstructed leaving the solid matter behind so that the overflow will not also become clogged.

The lower ends of the ascending passages of the siphon and overflow are on the same level so that they are both sealed simultaneously when water is supplied to 70 the bowl and thereby effectually prevent the entrance of sewer gas from entering the building either through the siphon or through the overflow.

I claim as my invention:

1. A water closet comprising a bowl, an outlet below the bowl, a siphon having an ascending passage extending upwardly from the bowl and a descending passage extending downwardly from the upper end of 80 said ascending passage to said outlet, and an overflow having an ascending passage extending upwardly from the bottom of said bowl and a descending passage extending downwardly from the upper end 85 of said last mentioned ascending passage to said outlet, the upper ends of the passages of the overflow being arranged higher than the upper ends of the passages of said siphon, and the capacity of the descending 90 passage of the overflow being greater than the companion ascending passage.

2. A water closet comprising a bowl, an outlet below the bowl, a siphon having an ascending passage extending upwardly 95 from the bowl and a descending passage extending downwardly from the upper end of said ascending passage to said outlet, and an overflow having an ascending passage extending upwardly from the bottom 100 of said bowl and a descending passage extending downwardly from the upper end of said last mentioned ascending passage to said outlet, the upper ends of the passages of the overflow being arranged higher 105 than the upper ends of the passages of said siphon, and the capacity of the descending passage of the overflow being greater than the companion ascending passage 110 and the lower ends of the ascending passages of the siphon and overflow being on the same level.

JOHN J. BOYNE.
